UNITED STATES PATENT OFFICE.

SAMUEL HELLER, OF NEW YORK, N. Y.

DESIGN FOR A PRECIOUS, SEMIPRECIOUS, SYNTHETIC, OR IMITATION STONE.

45,668.

Specification for Design.

Patented Apr. 28, 1914.

Application filed December 29, 1913. Serial No. 809,427. Term of patent 3½ years.

To all whom it may concern:

Be it known that I, SAMUEL HELLER, a citizen of the United States, residing in the borough of Manhattan, city, county, and State of New York, have invented a certain new, original, and ornamental Design for Precious, Semiprecious, Synthetic, or Imitation Stones, of which the following is a specification, reference being had therein to the accompanying drawing, forming part thereof.

Figure 1 shows a plan view of the stone

showing my new design. Fig. 2 is an end view of the same. Fig. 3 is a side view of the same.

I claim:

The ornamental design for a precious, semiprecious, synthetic or imitation stone, as shown.

SAMUEL HELLER.
